DESIGN FOR A HOBBYHORSE

Paul F. Gosswein and Ernst C. Gosswein,
Chicago, Ill.

Application October 4, 1943, Serial No. 111,267

Term of patent 7 years

To all whom it may concern:

Be it known that we, Paul F. Gosswein and Ernst C. Gosswein, citizens of the United States, residing at Chicago, in the county of Cook and State of Illinois, have invented a new, original, and ornamental Design for a Hobbyhorse, of which the following is a specification, reference being made to the accompanying drawing, forming a part thereof, in which

Fig. 1 is a side elevational view of a hobbyhorse embodying our new design;

Fig. 2 is a top plan view of the same;
Fig. 3 is a front end elevational view of the hobbyhorse shown in Figs. 1 and 2; and
Fig. 4 is a rear elevational view thereof.

We claim:
The ornamental design for a hobbyhorse, substantially as shown.

PAUL F. GOSSWEIN.
ERNST C. GOSSWEIN.
